FOLDING CADDY WAGON

Edwin J. Schwabe, New York, N. Y.

Application October 18, 1934, Serial No. 748,822

4 Claims. (Cl. 211—149)

This invention relates to new and useful improvements in articles of furniture and more particularly it pertains to articles of furniture of the type known as caddy wagons, serving 5 tables and the like.

It is one object of the invention to provide a new and novel construction whereby an article of furniture of the afore-mentioned type may be folded to a position wherein it will 10 occupy a relatively small space when not in use and yet is capable of rigid support when in its operative position.

It is another object of the invention so to construct the device that when it is in its extended or operative position, it will be rigid in 15 its support of one or more shelves or trays in a position to support articles placed thereon.

It is a further object of the invention so to construct the device that when in its extended or operative position it will be rigidly supported 20 and locked in such position against accidental collapsing.

It is a still further object of the invention so to construct the device that the shelves or 25 trays which constitute an important element thereof are permanently attached to the device in such a manner that they do not have to be removed from the device when it is operated to its collapsed position.

Other objects will appear as the nature of 30 the invention is better understood and reference will be had to the following specification and claims and to the accompanying drawing wherein:

Fig. 1 is a perspective view of a device constructed in accordance with the present invention, the same being illustrated in its extended or operative position.

Fig. 2 is a perspective view of the device in 40 its folded or collapsed position.

Fig. 3 is a view partly in elevation, and partly in section, of the device in its extended or operative position, and

Fig. 4 is a fragmentary perspective view on an 45 enlarged scale.

In its present embodiment, the device comprises a frame member which consists of two side members 10 and 11 and end members 12 and 13. The end member 13 is preferably spaced from the adjacent ends of the side members 10 and 11 for a purpose to be hereinafter described. Carried by the extended ends 15 of the side members 10 and 11, there are wheels, 50 castors or the like 16, by which the device may

be more easily moved along a floor or other support.

The reference numeral 19 designates a swinging foot which is pivotally mounted upon the end member 13 of the frame member as at 17. This foot is preferably mounted beneath the end member 13 of the frame member in the space provided by the spacing of said end member from the ends of the side members 10 and 11 of the frame member. This construction and 10 arrangement of parts permits of the swinging foot 19 moving into parallelism with the end member 13, to which it is pivoted, it being understood that the foot 19 will be shorter in length than the space between the extended ends 15 of the side members 10 and 11. Suitable wheels 15 or castors 18 are also provided upon the swinging foot 19.

Shelves or trays 20 are so constructed and arranged within the frame member that, when the device is folded up, they will occupy a position wholly within the confines of the frame member, as illustrated in Fig. 2, and as illustrated in Figs. 1 and 3 are capable of movement to a position at an angle to the plane of the 25 frame when the device is extended to its operative position. This is accomplished by pivotally mounting the shelves or trays 20, as at 24, in the side members 10 and 11 of the frame member.

Means is provided to maintain the shelves or 30 trays in their supporting position and this means preferably consists of a supporting leg 21 pivotally attached to the shelves or trays 20, by hinges 22, in such a manner that when the shelves or trays are moved to the position in 35 which they are shown in Fig. 2, the supporting leg 21 will swing about the hinges 22 to position against the rear faces of the shelves or trays 20.

The supporting leg 21 has interengagement 40 with the swinging foot 19 to maintain the shelves or trays in their supporting position and also to prevent swinging movement of the swinging foot 19. This interengagement of the supporting leg 21, with the swinging foot 19, is accomplished preferably by notching the lower end 45 of the supporting leg 21, as at 25, see Fig. 4, and notching the swinging foot 19, as at 26, in order that it may be received within the notch 25 of the supporting leg 19. The supporting leg 19 is also provided with an opening 28 for the reception of a locking bolt 29, carried by the swinging foot 19, when the supporting leg and swinging foot are in interengagement with each other.

In Fig. 2 the device is illustrated in its folded 55

or inoperative position, in which position all the movable parts are positioned in the same plane as the frame member and the device, in this position, will occupy a minimum amount of space.

When it is desired to set the device up in its operative position in which it is shown in Fig. 1, it is only necessary to move the swinging foot 19 about the pivotal point 17 to a position 10 at substantially right angles to the end member 13 of the frame, rock the shelves or trays about their pivotal points until the notch 25 of the supporting leg 19 embraces the notched portion 26 of the swinging foot 19, in which position 15 it will be apparent that the supporting leg 21 will rest upon the swinging foot 19 and will hold the shelves or trays 20 in their operative position. After the device has been operated as 20 just described, the bolt 29 is moved into the opening 28 and the device is locked in its set up position.

It will be noted that when the device is in its set up position, the supporting leg 21, in addition to supporting the shelves 20 in their operative 25 position, functions to prevent swinging movement of the swinging foot 19 about the pivotal point 17 and the consequent collapse of the device to a folded or partially folded position, and together with the bolt 29, insures rigidity of the 30 device in its set up position.

To move the device from its set up position to its knock-down, or folded, position, it is only necessary to disengage the bolt 29, swing the shelves or trays to position within the frame and swing 35 the foot 19 into parallelism with the member 13 of the frame as illustrated in Fig. 2.

While the invention has been herein illustrated in a preferred form, it is to be understood that it is not limited to the specific construction 40 and arrangement of parts herein shown and that it may be carried out in other forms within the scope of the appended claims.

Having thus described my invention, what I 45 claim as new and desire to secure by Letters Patent is:—

1. An article of furniture of the class described comprising a frame member adapted to be supported in upright position, a horizontally swinging foot pivotally mounted on one end of said frame member and adjustable to a position at 50 an angle to the plane of said frame member to support the frame member in an upright position, a plurality of supporting shelves or trays pivotally mounted in said frame member and means 55 carried by said shelves or trays for engagement

with said swinging foot to maintain said swinging foot in adjusted position.

2. An article of furniture of the class described comprising a frame member adapted to be supported in an upright position, a horizontally swinging foot carried by one end of said frame member, said swinging foot being adjustable to a position at an angle to the frame member to support the frame member in an upright position, shelves or trays pivotally mounted in the sides of said frame member, said shelves or trays being movable to a position wholly within the confines of said frame member or to a supporting position at an angle thereto, and means carried by the shelves or trays and adapted for engagement with the afore-mentioned swinging foot for maintaining the shelves or trays in their supporting position.

3. An article of furniture comprising a frame member adapted to be supported in an upright position, a horizontally swinging foot carried by one end of said frame member, said swinging foot being adjustable to a position at an angle to the frame member to support the frame member in an upright position, shelves or trays pivotally mounted in the sides of said frame member, said shelves or trays being movable to a position wholly within the confines of said frame member or to a supporting position at an angle thereto, and a shelf or tray supporting leg carried by said shelves or trays and having interengagement with said swinging foot to support said shelves or trays in their supporting position and to lock said swinging foot in its frame member supporting position.

4. An article of furniture comprising a frame member adapted to be supported in an upright position, a horizontally swinging foot carried by one end of said frame member, said swinging foot being adjustable to a position at an angle to the frame member to support the frame member in an upright position, shelves or trays pivotally mounted in the sides of said frame member, said shelves or trays being movable to a position wholly within the confines of said frame member or to a supporting position at an angle thereto, a shelf or tray supporting leg carried by said shelves or trays and having interengagement with said swinging foot to support said shelves or trays in their supporting position and to lock said swinging foot in its frame member supporting position, and means for maintaining said shelf or tray supporting leg in interengagement with said swinging foot.
